UNITED STATES PATENT OFFICE.

VITO GIORGIO SANGIORGIO, OF MERIDEN, CONNECTICUT.

MACARONI AND SPAGHETTI MACHINE.

1,266,720.

Specification of Letters Patent. Patented May 21, 1918.

Application filed August 2, 1917. Serial No. 184,049.

To all whom it may concern:

Be it known that I, VITO GIORGIO SANGIORGIO, a citizen of the United States, residing in Meriden, county of New Haven, State 5 of Connecticut, have invented a certain new and useful Macaroni and Spaghetti Machine, of which the following is a specification.

This invention is a macaroni and spaghetti machine, and the object of the invention is 10 to provide a machine of this character which may be employed for family use, so that macaroni, spaghetti, etc., may be made fresh when desired, thereby obviating the necessity of employing the dry product which, 15 admittedly is much inferior in taste to the product when fresh.

With the foregoing object in mind, the present invention embodies a remarkably simple form of mechanism which is preferably 20 operated by hand and will form macaroni or spaghetti in the shapes in which they are generally placed on the market, but which may be readily operated in the kitchen of a household to form the products from 25 material mixed just prior to its introduction into the machine. Through the employment of this invention, the spaghetti or macaroni may be formed and baked, or otherwise prepared, immediately following the mixing of 30 its constituents.

Machines have heretofore been suggested for making macaroni in the home, but these machines have generally been complicated and have been open to the objection that the 35 macaroni could only be made arcuate in cross-section or solid, and not cylindrical, as is preferred. According to the present invention, cylindrical macaroni results from the operation of the machine, and this in 40 practice is found to produce the most palatable dishes.

Features of the invention, other than those specified, as well as the advantages thereof, will be apparent from the hereinafter detailed description taken in conjunction with 45 the accompanying drawing.

In the accompanying drawing I have illustrated one practical embodiment of the invention, but the construction therein shown 50 is to be understood as illustrative, only, and not as defining the limits of the invention.

Figure 1 is a side elevation of a machine embodying the present invention, a part of the casing of the machine being broken away, 55 and the macaroni forming parts being shown

in section on the line 1—1 of Fig. 2, in the interest of clearness.

Fig. 2 is a front elevation of the machine.

Fig. 3 is a section on line 3—3 of Fig. 2.

Fig. 4 is an inside view of the face or 60 forming plate of the machine, and

Fig. 5 is a face view of a filler member employed in conjunction therewith.

Referring to the drawings, A indicates the casing of the machine, which is provided 65 with a depending stem B, the lower end of which is shaped to form a clamp whereby the casing may be mounted rigidly upon a firm support. Casing A is provided with a horizontal, cylindrical portion C, to the rear 70 portion of which material may be fed through a hopper D. A helical conveyer screw E is operable within cylindrical portion C and is provided with a stem e to which is secured an actuating crank e'. 75

It will be noted that the construction as thus far described is the same, in effect, as the well known domestic food chopper of a form extremely compact, durable, and highly efficient. The present invention, however, 80 differs from the ordinary food chopper in that, instead of feeding the material by conveyer screw E between knives at the forward end of cylindrical portion C, said screw serves to force dough, embodying macaroni 85 or spaghetti constituents, forwardly through means associated with the front end of cylindrical portion C, whereby said dough takes on a tubular form and is adapted to be cut off into the desired lengths by means next to 90 be described.

The forward end of cylindrical portion C is open and is provided with a tapered seat for a similarly tapered plug F, which will hereinafter be termed the face-plate. Said 95 plate is provided at its opposite sides with apertured lugs f, through the apertures of which lugs screws f' may be threaded into lugs c in the casing for the purpose of maintaining the face-plate seated within the tapered end of the cylindrical portion. The face-plate is provided with an annular series of apertures g, and on the inner side of said plate the apertures are countersunk as at g', 100 as shown best in Figs. 3 and 4.

I designates the filler member, which is substantially star-shape, on the arms of which star, which are equal in number to the number of apertures g, are mounted pins i, positioned in corresponding relation on 110

member I as the apertures g formed in plate F. Member I is adapted to be seated within the recess or depression f^2 in the inner face of plate F and partakes of the position 5 shown in Fig. 3, wherein the back face of member I is substantially flush with the corresponding face of face-plate F, with one of the pins i extending through each aperture g . As shown in Fig. 3, the pins i are 10 of less diameter than are the apertures g , and the space left between the parts is equal to the thickness of the wall of the macaroni to be formed.

It will be seen from Fig. 3 that, if the plastic material is forced against the back of 15 plate F, it will squeeze forwardly through apertures g and around pins i , the countersunk portions g' allowing of sufficient clearance between the arms of filler member I 20 and the walls of the countersinks to leave ample space for the passage of said material through the apertures g in such manner that it will completely surround pins i . Thus, if dough embodying the constituents of 25 macaroni is introduced into the casing through hopper D, it will be fed forwardly by conveyer screw E and forced through the face-plate and around pins i , which operation will result in the constant feed of tu- 30 bular macaroni from the several openings g , as long as the crank c' is operated and the material fed to the machine.

It is desirable that means be provided for cutting the macaroni thus formed into desired lengths, and, in the form of the invention shown, this means is associated with the stem j of conveyer screw E. This stem projects through a central aperture in face-plate I, as shown in Fig. 1, and is provided 35 at its outer end with a threaded portion 40 adapted to receive a wing nut J by which the conveyer screw is precluded from working out of the back of the machine. Intermediate screw J and the front of plate F is 45 pivoted a knife K, which may be oscillated, by means of a handle k , about stem j of screw E. By rotating the knife as described, the tubular macaroni extending through and beyond the apertures g may be 50 cut off flush with the front face of plate F. Knife K normally gravitates into the idle position shown in Figs. 1 and 2, but may

be manually operated to cut off the macaroni as the desired lengths thereof are successively formed.

It will be understood that the macaroni or spaghetti thus formed is deposited in a suitable receptacle and thereafter preferably placed in a heated oven to be dried sufficiently for its proper use.

A marked advantage of the present invention over prior art devices resides in the fact that, because of the coöperating face-plate and filler member, tubular macaroni may be produced, this being due to the fact 65 that the filler member coöperates with the face-plate in such manner that the outlines of the apertures in the face-plate are entirely unobstructed circumferentially. Thus, the circumference of each aperture imparts 70 a cylindrical configuration to the macaroni, while the pins i render said macaroni hollow. The macaroni thus formed is, accordingly, tubular, and the walls thereof are of substantially equal thickness throughout, so 75 that the macaroni will cook evenly and will result in a most palatable product.

Having thus fully described the invention, what I claim as new, and desire to secure by Letters Patent, is:

In a machine of the character described, the combination of a cylindrical barrel, means for forcing dough longitudinally therethrough, a face-plate at the forward end of the barrel provided on its inner face 85. with a recess and having a plurality of counter-sunk apertures extending through the face-plate, a filler member, a portion of which is shaped to seat in the recess in the inner face of said plate with the inner side 90 of the filler member substantially flush with the inner side of the plate, and a plurality of projections on the filler member extending forwardly into the centers of the apertures of the face-plate to form each aperture into a centrally cored passage, whereby 95 the dough is forced into the countersinks, circulates thereabout, and is forced through the passages to issue therefrom in tubular form.

In testimony whereof I have signed my name to this specification.

VITO GIORGIO SANGIORGIO.
